DESIGN.

—o—

F. MANKEY.

MOLDING.

No. 16,955.

Patented Oct. 26, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,955, dated October 26, 1886.

Application filed July 12, 1886. Serial No. 207,845. Term of patent 7 years.

To all whom it may concern:

Be it known that I, FREDERICK MANKEY, of Williamsport, Lycoming county, Pennsylvania, have invented and produced a new and original Design for Ornamental Trims or Moldings, of which the following is a specification, reference being had to the accompanying photograph, forming part hereof.

My design relates to an ornamental trim or molding; and it consists in the configuration thereof, substantially as herein shown and described.

One edge, C, of the trim is straight. On the other edge appear serrations or V-shaped projections A, alternating with straight portions B. On the face of the trim and near the edge appear elongated elevations or bars D. I may show one or more of said elevations, three being exhibited in the photograph. Also, on the face of the trim appear transverse scores E F, which extend to the points of junction of the edge serrations A and straight portions B. Between the scores E F, and on the face of the bar proximate to a serration, appears an annular recess, G, from which diverge lenticular depressions H I J. Two of said depressions, H J, are placed diagonally and the center one, I, transversely the trim.

I claim—

1. The design for an ornamental trim or molding, substantially as herein shown and described, which consists in the V-shaped serrations or projections A, with intermediate straight portions, B, on one edge of said trim, the opposite edge being straight, and on the face of said trim a longitudinal elevation, D, and transverse channels E F.

2. The design for an ornamental trim or molding, substantially as herein shown and described, which consists in the V-shaped serrations or projections A, with intermediate straight portions, B, on one edge of said trim, the opposite edge being straight, and on the face of said trim a longitudinal elevation, D, transverse channels E F, and lenticular depression I.

3. The design for an ornamental trim or molding, substantially as herein shown and described, which consists in the V-shaped serrations A, with intermediate straight portions, B, on one edge of said trim, the opposite edge being straight, and on the face of said trim a longitudinal elevation, D, transverse channels E F, and lenticular depressions H J.

FREDERICK MANKEY.
